UNITED STATES PATENT OFFICE.

ROBERT S. BLAIR, OF NEW ROCHELLE, NEW YORK, ASSIGNOR TO INTERNATIONAL TIME RECORDING COMPANY OF NEW YORK, OF ENDICOTT, NEW YORK, A CORPORATION OF NEW YORK.

WORKMAN'S TIME-RECORDER.

1,040,859.

Specification of Letters Patent.

Patented Oct. 8, 1912

Application filed September 25, 1907, Serial No. 394,513. Renewed March 29, 1911. Serial No. 617,738.

To all whom it may concern:

Be it known that I, ROBERT S. BLAIR, a citizen of the United States, residing at New Rochelle, in the county of Westchester and State of New York, have invented certain new and useful Improvements in Workmen's Time-Recorders, of which the following is a full, clear, and exact description, such as will enable others skilled in the art to which it appertains to make and use the same.

This invention relates to time recording apparatus.

One of the objects thereof is to provide a practical and efficient workmen's time recorder, in which records of different classes are readily distinguished.

Another object is to provide a time recorder of the above type, characterized by the accuracy of action and economy of power.

Another object is to provide a time recorder in which power is taken during the use of the instrument and stored for use in operating certain parts thereof.

Another object is to provide simple and practical means for shifting a printing ribbon in a lateral direction.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings wherein is shown one of various possible embodiments of this invention: Figure 1 is a sectional front elevation thereof. Fig. 2 is a sectional side plan of the same. Fig. 3 is a sectional side elevation taken substantially on the line X-X of Fig. 1. Fig. 4 is a detail view of spring mechanism. Fig. 5 is a detail perspective view of locking and releasing mechanism.

Similar reference characters refer to similar parts throughout the several views of the drawings.

Referring now to Fig. 1 of the drawings, there is shown a casing 1 having journaled in its side walls rock shaft 2, upon which is fixed an actuating lever 3. Also mounted upon the rock shaft 2 is a crank arm 4 con-

nected as by a link 5 with a swinging platen 6. Platen 6 is adapted to co-act with printing wheels 7 and 8 driven from clock-work 9 in any desired manner. Mounted upon the casing 1 adjacent the printing wheels 7 and 8 is a card receiver 10 of any desired construction adapted to hold a record card in any desired position to receive an impression from the type wheels upon being forced against the same by the platen 6.

It is to be understood that the above described parts are somewhat diagrammatically shown and various adjustments such as a lateral movement of the card receiver are omitted, as they in themselves form no part of the present invention.

Mounted between the type wheels and the card receiver 10 is a printing ribbon 11 comprising a plurality of differently colored portions as 12 and 13 adapted to impart corresponding colors to the record upon the same being brought in operative relation to the type wheels and record card. This ribbon 11 is mounted upon spools 14 which are slidably mounted upon upright spindles 15, and, the latter being driven in any desired manner, are adapted to be driven thereby as by the splined connection 16. The ribbon 11 is laterally shifted by means of forked arms 17 upon a rock shaft 18, these arms being provided with pins 19 taking into grooved collars 20 upon the spools 14. It will thus be seen that upon the rock shaft 18 occupying a position in which the pins 19 are depressed the portion 12 will be in operative relation to the type wheels, and is adapted to be driven through the spline 16 as above noted. If, however, the rock shaft 18 be swung to elevate the pins 19 the spools 14 are drawn upwardly to bring the ribbon portion 13, which is of a different color, in operative relation to the type wheels and cause a corresponding change in the color of the record formed by the instrument.

The means by which the oscillation of the rock shaft 18 is brought about comprise an arm 21 fixed thereon and provided with a roller 22 entering the sinuous groove 23 of a cylindrical cam 24. This cam is so formed as upon being turned throughout a predetermined degree to swing the arm 21 from one extreme to another and thus bring about a corresponding lateral shift of the printing ribbon. Cam 24 is mounted upon a shaft 25

journalized within suitable bearings 26 and having secured thereto one end of a coiled spring 27. The opposite end of this spring is secured to a casing 28 loosely journaled upon the shaft 25 and provided with a ratchet connection 29 whereby it is held fast, and permits the spring 27 to exert its force upon the shaft 25. The winding of spring 27 is brought about by a casing 30 loosely fitted about the casing 28 and provided on its outer surface with ratchet teeth 31. These teeth are engaged by a pawl 32 upon a link 33 pivotally connected with an arm 34 upon the shaft 2. It will thus be seen that suitable guides for the pawl 32 being provided the same will be forced downwardly at each depression of the actuating or printing lever 3, and turn the casing 30 throughout a portion of a revolution. This movement with the spring in a wound or coiled condition exerts no effect upon the latter member, but if the spring be unwound as indicated in Fig. 4 of the drawings, it engages a locking pin 35 slidably mounted in an opening in the casing 28 and normally urged inwardly by a spiral spring 36 against the outer coil of spring 27. In casing 30, moreover, are a number of openings 37 adapted to register with the pin 35 and upon the spring becoming nearly unwound, as indicated in Fig. 4 of the drawings, this pin is pressed outwardly and through one of these openings 37, thus locking together the casings 28 and 30. With the parts in this condition the casing 28 will be rotated as the instrument is used, and the spring again wound up, whereupon pin 35 is withdrawn to an inoperative condition by the spring 36. By this mechanism the shaft 25 is constantly urged in a predetermined direction, deriving its energy for this movement from the hand of the workmen in using the instrument. It may be here noted that a spring wound or distorted in this manner may be utilized in driving other parts of the recorder than the ribbon shifting mechanism if desired. It may also be noted that the term "distort" is used throughout this description and the following claims with reference to a spring as denoting any change from its normal free state, whether the same be bending, coiling, twisting or otherwise.

Mounted upon shaft 25 are a pair of members 38 and 39 provided with roller pins 40 and 41 extending from the same in radial directions. Pins 40 are adapted to co-act with a disk 42 provided with a slot 43 adapted upon the registry with the pins, to permit the same to pass therethrough. Pins 41 are mounted to co-act with disks 44 and 45 upon an upright shaft 46 as best indicated in Fig. 5 of the drawings. The upper disk 44 is provided with slots or openings 47, whereby the pins 41 may pass through the same and rest against the disk 45; and

the latter member is provided with slots 48, whereby a pin resting upon the lower disk may at a predetermined time pass through the same, and permit the next of the pins 41 to rest upon the disk 44. The shaft 46, as well as shaft 49, upon which the disk 42 is mounted, are driven in any desired manner from the clock-work and preferably at such rates as to cause the former shaft to rotate once in 24 hours and shaft 49 to rotate once in 15 minutes.

The operation of the above described embodiment of this invention is substantially as follows: Assuming that it be desired that during the hours of labor the ribbon portion 12 is to be in operative relation to the type wheels, and out of hours of labor the portion 13 is to be in such relation, it will be seen that by the mechanism above described this may be brought about by the advancing 80 of cam 24 throughout the proper distance at a predetermined time. Shaft 25 upon which cam 24 is mounted is, as has been above shown, constantly urged in such direction as to force the pins 40 and 41 against the several slotted disks. The disk 44 is provided with a slot 47 in such position and so driven as to come opposite the pin 41 at the beginning of the hours of labor as 90 7.00 in the morning. On account of the slow movement of this disk, accurate adjustment might be necessary to release the pin 41 at a predetermined instant, but it is to be noted that this pin with the shaft 25 is not released until the slot 43 of disk 42 is brought 95 opposite the corresponding pin 40. The latter relatively fast moving member brings its slot into registering position at precisely the desired instant, and the pin 41 then falls upon the disk 45. This movement of shaft 100 25 shifts the ribbon to bring another color in operative relation by the mechanism above described. To shift the ribbon back again at the end of the period of labor, a slot 48 in disk 45 comes under the pin 41, which has passed the disk 44 and is resting 105 against disk 45. The next pin 40, there being twice as many pins 40 as pins 41, is then released at the proper time by the disk 42, and the following pin 41 is permitted to 110 drop upon the top disk 44. This pin is in turn released by a proper slot in the disk 44, and it will be seen that by means of this disk 115 the ribbon may be shifted at any desired time, and that such action will occur at precisely the desired instant. It will thus be seen that there is provided a source of power, namely the coiling spring 27, which is potentially adapted to shift the ribbon, and that this power becomes active at predetermined times, governed by the clock-work. It may here be noted that the terms 120 of the nature of "potential" are used throughout this description and the following claims in a broad sense to denote any 125 130

temporarily inactive form of energy, whether of mechanical or electric nature or otherwise.

It will thus be seen that I have provided mechanism in which the several objects of this invention are achieved, and the above enumerated advantages are among others present.

The entire mechanism is simple and inexpensive, and not likely to become deranged, and the action of the parts is positive and accurate.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

I claim—

1. In a time recorder, in combination, record forming mechanism, record-changing means comprising a spring adapted to change a characteristic of records formed by said mechanism, hand actuated means adapted to distort said spring, and clock-controlled means adapted to release said spring 25 to actuate said record-changing means, said clock-controlled means being formed and driven to release said spring only at the beginning and terminal points of periods of labor.

2. In a time recorder, in combination, printing wheels, a multi-colored ribbon mounted adjacent said printing wheels, means comprising a spring adapted to shift said ribbon to change the color thereof in 35 operative relation to said printing wheels, hand actuated means adapted to distort said spring, and clock-controlled means adapted to release said spring to actuate said ribbon shifting means.

3. In a time recorder, in combination, printing wheels, a multi-colored ribbon mounted adjacent said printing wheels, means comprising a spring adapted to shift said ribbon to change the color thereof in 50 operative relation to said printing wheels, hand actuated means adapted to distort said spring, and clock-controlled means adapted to release said spring to actuate said ribbon shifting means, said clock-controlled means 55 being formed and driven to release said spring at the beginning and terminal points of periods of labor.

4. In a time recorder, in combination, record forming mechanism, means comprising a source of power potentially adapted to 60 change a characteristic of records formed by said mechanism prior to the beginning and terminal points of periods of labor, and clock-controlled means adapted only at the 65 beginning and terminal points of said peri-

ods of labor to render operative said source of power.

5. In a time recorder, in combination, printing wheels, a multi-colored ribbon mounted adjacent said wheels, means comprising a spring adapted to shift said printing ribbon in a direction to change the color of the portion thereof in operative relation to said wheels, hand actuated means adapted to distort said spring prior to the beginning 70 and terminal points of periods of labor, and clock-controlled means adapted to release said spring to shift said ribbon at said beginning and terminal points, said spring being adapted upon being distorted to store 80 power to shift said ribbon a plurality of times.

6. In a time recorder, in combination, printing wheels, a multi-colored ribbon mounted adjacent said wheels, means comprising a source of power potentially adapted 85 to shift said printing ribbon to change the color thereof in operative relation to said printing wheels, and clock-controlled means adapted to render said source of 90 power operative at the beginning and terminal points of periods of labor.

7. In a time recorder, in combination, printing wheels, a multi-colored ribbon mounted adjacent said printing wheels, 95 means comprising a spring adapted to shift said ribbon to change the color thereof in operative relation to said printing wheels whereby the energy for shifting said ribbon is derived from said spring, means adapted 100 to release said spring to shift said ribbon, and clock work controlling said releasing means to render records formed within periods of labor of a distinctive color.

8. In a time recorder, in combination, 105 printing wheels, a multi-colored printing ribbon, ribbon spools having mounted thereon said printing ribbon and slidably mounted adjacent said printing wheels, a rock-shaft connected with said spools, and adapted to shift said ribbon laterally, means comprising a spring adapted to oscillate said rock shaft, hand actuated means adapted to distort said spring, and clock controlled means adapted to release said spring and 110 permit the same to shift said ribbon.

9. In a time recorder, in combination, printing wheels, a multi-colored printing ribbon, ribbon spools having mounted thereon said printing ribbon and slidably mounted adjacent said printing wheels, a rock shaft connected with said spools, and adapted to shift said ribbon laterally, an arm upon said rock shaft, a cam provided with 115 a sinuous groove adapted to engage said arm and oscillate said rock shaft and time-controlled means adapted to affect the action of said cam.

10. In a time recorder, in combination, 120 record forming means, means comprising a 125

source of power potentially adapted to change a characteristic of records formed thereby, a pair of clock driven members, and means depending upon the conjoint action 5 of said members adapted to render said source of power operative to change a characteristic of the records.

11. In a time recorder, in combination, record forming means, means comprising a 10 source of power potentially adapted to change a characteristic of records formed thereby, a pair of clock driven members, and means depending upon the conjoint action 15 of said members adapted to render said source of power operative to change a characteristic of the records, said clock-driven members being driven at different rates of speed.

12. In a time recorder, in combination, 20 printing wheels, a multi-colored printing ribbon mounted adjacent said printing wheels, means comprising a spring adapted to shift said ribbon to bring a portion of a different color in operative relation to said 25 printing wheels, hand actuated means adapted to distort said spring, a pair of clock-driven members, and means controlled by the conjoint action of said members adapted to release said spring and cause the shifting 30 of said ribbon.

13. In a time recorder, in combination, 35 printing wheels, a multi-colored printing ribbon mounted adjacent said printing wheels, means comprising a spring adapted to shift said ribbon to bring a portion of a different color in operative relation to said printing wheels, hand actuated means adapted 40 to distort said spring, a pair of clock-driven members, and means controlled by the conjoint action of said members adapted to release said spring and cause the shifting 45 of said ribbon, said clock-driven means being driven at different rates of speed, and being so formed and so driven as to permit the release of said spring at the beginning and terminal points of periods of labor.

14. In a time recorder, in combination, 50 printing wheels, a multi-colored printing ribbon mounted adjacent said printing wheels, means comprising a spring adapted to shift said ribbon to bring a portion of a different color in operative relation to said printing wheels, hand actuated means adapted 55 to distort said spring, a pair of clock-driven members, and means controlled by the conjoint action of said members adapted to release said spring and cause the shifting of said ribbon, each of said clock-driven members being formed and positioned to in-

dependently prevent the release of said 60 spring.

15. In a time recorder, in combination, record forming means, an actuating lever adapted to operate said record forming means, record-changing means comprising a 65 spring adapted to change the color of the records formed, means connecting said spring with said lever whereby said lever is adapted to distort the same, and clock actuated means adapted to release said spring to 70 actuate said record-changing means.

16. In a time recorder, in combination, 75 printing wheels, a multi-colored printing ribbon mounted adjacent the same, an actuating lever adapted to cause said printing 80 wheels to form a record, means comprising a spring adapted to shift said ribbon to change the color thereof in operative relation to said printing wheels, connecting means between said actuating lever and said spring whereby said lever is adapted to distort said spring, and clock-controlled means adapted to release said spring and cause the shifting of said ribbon.

17. In a time recorder, in combination, 85 printing wheels, a multi-colored printing ribbon mounted adjacent the same, an actuating lever adapted to cause said printing wheels to form a record, means comprising a spring adapted to shift said ribbon to 90 change the color thereof in operative relation to said printing wheels, connecting means between said actuating lever and said spring whereby said lever is adapted to distort said spring, clock-controlled means 95 adapted to release said spring and cause the shifting of said ribbon, and means controlled in accordance with the condition of said spring adapted to render said connection inoperative.

18. In a time recorder, in combination, 100 printing wheels, a multi-colored printing ribbon mounted adjacent said wheels, means comprising a source of power potentially adapted to shift said printing ribbon to 105 change the color thereof in operative relation to said printing wheels, and means adapted to render said source of power operative to shift said ribbon to render records formed within working hours of a distinctive color.

In testimony whereof I affix my signature, in the presence of two witnesses.

ROBERT S. BLAIR.
